CLAIM

The ornamental design for a retractable pet gate as shown and described.

DESCRIPTION

FIG. 1 is a perspective view of a retractable pet gate showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the retractable pet gate where the retractable pet gate is in a folded state;

FIG. 10 is an exploded perspective view of the retractable pet gate;

FIG. 11 is a perspective view of the retractable pet gate where the retractable pet gate is in a first configuration of use; and,

FIG. 12 is a perspective view of the retractable pet gate where the retractable pet gate is in a second configuration of use.

The dash-dash broken lines immediately adjacent to the shaded areas depict the bounds of the claimed design, and form no part of the claimed design. The dash-dash broken lines showing additional gate panels in FIGS. 11 and 12 depict environmental structure and form no part of the claimed design. The remaining dash-dash broken lines in the drawings depict portions of the retractable pet gate that form no part of the claimed design.
